BRACELET

Application filed February 20, 1929. Serial No. 341,454.

Our invention has reference to an improvement in the art of jewelry and more particularly to an improvement in watch bracelets constructed of metal, which may be of any kind desired.

The object of our invention is to improve the construction of such a watch bracelet, whereby, the bracelet is of a helical spring construction, a pleasing and novel design in 10 watch bracelets is produced and the cost of manufacturing the bracelet is reduced to a minimum.

Our invention consists in the peculiar and novel construction of a watch bracelet, said 15 watch bracelet having details of construction, as will be more fully set forth hereinafter and claimed.

Figure 1 is an edge view of our improved bracelet in approximately the position it 20 would assume when in use.

Figure 2, is an inner face view of one end portion of the bracelet in a flattened out position, to more clearly show its construction, both ends of the bracelet being constructed 25 alike.

Figure 3 is a longitudinal sectional view through the snap hook end and part of the body of the bracelet, taken on line 3, 3, of Figure 2.

Figure 4 is a transverse sectional view through the bracelet, taken on line 4, 4, of Figure 2, and

Figure 5, is a perspective view of a portion of the S shaped strip of metal of which the 35 body of the bracelet is formed.

Figure 1 is enlarged and Figures 2, 3, 4 and 5, are greatly enlarged to more clearly show our new and novel construction of the bracelet.

40 In the drawing 6, indicates the body of the bracelet and 7, 7, the snap hooks on the ends of the bracelet body 6, and secured to the ends of the body 6, as will be hereinafter described.

45 The body 6, of the bracelet is constructed of a flexible nonelastic strap shaped metal fabric. The strap shaped body part, of the bracelet is formed of a corrugated strip of metal 9, approximately S shaped in cross section and having the longitudinal edges 10

and 11, which extend from the ends of the letter S, a longitudinal top corrugated portion 12, having an under longitudinal groove 13, and a longitudinal bottom corrugated portion 14, having a top longitudinal groove 15. 55

The corrugated strip of metal 9, is wound helically around a flat mandrel the interior shape and size of the bracelet, so that the edge 10, of the strip 9, extends over and into the top groove 15, of the strip 9, as shown in Figure 3. This operation is continual until any length required of bracelet body stock is obtained. It is then cut up into bracelet body lengths as required.

By this construction the entire length of 65 the bracelet body 6, has formed on it a continuous series of external corrugations 16, 16, made from the corrugated portion 12, of the strip 9. The bracelet body 6 is in the form of a helical spring which may be expanded nearly the width of the grooves 13 and 15, and which will contract into its closed position, as shown in Figure 3.

Each snap hook 7, is formed of sheet metal 75 to have a flat tubular end 17, shaped first to slip over the end of the bracelet body 6, a hook shaped end 18, and a spring tongue 19, as shown in Figures 1, 2 and 3. The end portion of the bracelet body 6, with the snap hook tubular end 17, on it, is placed between corresponding corrugated dies and the tubular end 17 of the snap hook 7, compressed onto the end portion of the body member 6, thereby locking the snap hook tubular end 17, onto the end portion of the bracelet by forming 80 coinciding corrugations 20, 20, on the end 17, of the snap hook 7, over the under corrugations 16, 16, of the bracelet body 6, and these corrugations 20, 20, form a continuation of the corrugations 16, 16, on the body 6, of the 85 bracelet, as shown in Figures 2 and 3.

By this construction and when in use, there is the required amount of elasticity in the body 6, of the bracelet, the snap hook ends 7, 7, are positively secured or locked to the 95 ends of the bracelet body 6, without soldering, the bracelet has a very pleasing effect to the eye and as it has only three parts, it can be manufactured at a minimum cost.

We do not confine ourselves to the exact 100

construction shown of the strip of metal 9, as this can be made plain, engraved or embossed and the letter **S** shape of the metal strip may be varied in form, so as to produce different effects of the corrugations on the bracelet.

Having thus described our invention we claim as new:—

1. A bracelet body constructed of one strip of metal **S** shaped in cross section and having corrugations extending lengthwise of the strip, the strip of metal being wound on itself and forming a spring bracelet body with external corrugations, snap hooks on the ends 15 of the bracelet and having corrugations coinciding with the corrugations on the bracelet.

2. A bracelet body constructed of one strip of metal **S** shaped in cross section, corrugations and grooves extending longitudinally 20 of the strip, the strip being helically wound on itself with the edges of the corrugations extending into the grooves of adjacent wound portions of the strip, and forming a spring bracelet body with external corrugations extending at an angle across the bracelet body, snap hooks on each end of the bracelet body, 25 each snap hook having an external corrugated portion extending over the end portions of the bracelet, the corrugations on the snap hook coinciding with the corrugations on the bracelet, and forming a continuation of the corrugations on the bracelet, said corrugated portion of the snap hook being compressed onto the corrugated end portions of 30 the bracelet body, thereby securing the snap hooks to the bracelet body, for the purpose 35 as described.

In testimony whereof, we have signed our names to this specification.

40   FREDERICK WILLIAM BOPP.
                  KARL LUDWIG VOLK.
